*Primary Examiner—Susan J. Lucas**Attorney, Agent, or Firm—Gregg I. Anderson*[57] **CLAIM**

The ornamental design for a light with linear lamp bulb, as shown and described.

DESCRIPTION

FIG. 1 is a perspective view of the light with linear lamp bulb of my new design;

FIG. 2 is a front elevational view thereof;

FIG. 3 is a rear elevational view thereof;

FIG. 4 is a top plan view thereof;

FIG. 5 is a bottom plan view thereof; and,

FIG. 6 is a left elevational view thereof, the right elevational view being a mirror image thereof.

Fig. 4
